UNITED STATES PATENT OFFICE.

ADRIAN H. HOYT, OF PENACOOK, NEW HAMPSHIRE.

SPRING TORSION-ROD FOR AUTOMOBILES.

1,202,389.

Specification of Letters Patent.

Patented Oct. 24, 1916.

Application filed March 27, 1916. Serial No. 87,103.

To all whom it may concern:

Be it known that I, ADRIAN H. HOYT, a citizen of the United States, residing at Penacook, in the county of Merrimack and 5 State of New Hampshire, have invented a new and useful Spring Torsion-Rod for Automobiles, of which the following is a specification.

The object of my invention is to provide 10 a torsion rod device having a novel and improved operation by reason of its inherently resilient character; and it is a further object of my invention to provide a 15 spring torsion rod of novel symmetrical form to afford the greatest strength at the portion where the strain is greatest.

Heretofore the torsion rod has always been a rigid member which allows the shocks to some extent to be transmitted to 20 the frame, even though supported by springs at its forward end, and which is open to the further objection that it causes greater strain upon the differential and transmission than takes places with my improved spring torsion device.

One of the principal advantages derived 30 from the use of this device is that a part of the shock caused by meeting stones or obstructions in the road is transmitted to the rear axle housing instead of the whole of the shock being transmitted to the frame of the car as is the case with the usual devices.

I attain the objects of my invention by the mechanism illustrated in the accompanying drawings, in which—

Figure 1 is a top plan of my invention; Fig. 2 is a side elevation; Fig. 3 is a section on line 3—3 of Fig. 2; Fig. 4 is a detail sectional view; Fig. 5 is a detail of member 40 8; and Fig. 6 is a diagrammatic illustration of the operation of the invention.

Like characters of reference designate like parts throughout.

Referring to the accompanying drawings, 45 I provide in place of the usual rigid torsion rod, a spring torsion device consisting of a main leaf member 1 having an eye member 3 at each end, and having a plurality of opposite leaf spring members 2 disposed on 50 opposite sides of member 1 in symmetrical arrangement, as illustrated in Fig. 2, and having means for retaining the leaf spring members in engagement. This means consists preferably of U-bolts 6, washers 15 and nuts 7. Members 6 engage around a plate 4, from which depends hinge member 5. From the latter member, rod 11, which is pivotally engaged to member 5 at 12, extends to the lower end of rod C, the eye portion 13 being hinged to the lower end of rod C by a suitable bolt 14, as illustrated in Fig. 4. The forward end of member 1 is pivotally secured to link 8, by member 9, as illustrated in Fig. 5. Link 8 is pivotally suspended from the cross member B of the 65 automobile frame. A designates the axle housing and C the usual vertical rod to which the torsion rod is connected.

The operation of my invention is indicated diagrammatically in Fig. 6. When 70 the wheel encounters an obstruction D the shock is transmitted to the differential so that the rear axle housing A would attempt to turn clockwise. This would result in a new position of the spring device and rod 75 11, as indicated approximately in the diagram (Fig. 6) in dotted lines. A downward pull is exerted on the spring device by the rod 11, at the same time rod C is rotated slightly forward by the axle housing A. 80 Part of the force exerted along rod 11 by reason of its movement in a rearward direction when an obstacle is encountered would be borne by the rear axle housing A and part supported from the cross member of 85 the frame B. The operation of rod 11 in thus transmitting a part of the downward pull caused by a road shock to the rear axle housing A is of great importance because it tends to hold the rear wheels down to the 90 ground, whereas the ordinary effect of bumps or road obstructions is to throw the rear end off from the ground, which makes a car ride hard. In other words, a part of the force exerted by the additional torque 95 necessary to overcome an obstruction encountered in the road is transmitted through the spring device and rod 11 to the axle housing and expended in holding the rear end of the car down. It will be seen therefore that the device has functions in addition to those performed by the ordinary torsion rod. It absorbs all shocks of starting and stopping and keeps road shocks from being transmitted to the frame of the 100 car. By reason of the symmetrical arrangement of the leaf spring members an equal resistance is exerted to either an upward or a downward pressure. The device exerts less strain upon the differential and transmission than the usual rigid torsion rod because the turning torque of starting and 110

stopping is absorbed gradually instead of suddenly. The symmetrical arrangement of the leaf spring members of the device and its connection with rod 11 affords the required reinforcement at the portion of the device where the strain is greatest and provides a device of much greater resilience than the small and stiff spiral springs customarily employed with the usual rigid torsion rod member.

10 What I claim is:

1. A spring torsion rod having a central leaf spring member and having opposite reinforcing leaf members of graduated lengths, 15 means pivotally connecting one end of the spring tension rod with the differential casing, and means supporting the other end.

2. A spring torsion rod having a central leaf member and having opposite reinforcing members of graduated lengths, means pivotally engaging one end of the spring torsion rod with means rigidly secured to the differential casing, and link means pivotally connecting the other end of the 20 spring tension rod with a cross member of the automobile frame.

3. Spring torsion rod mechanism comprising a symmetrically formed leaf spring torsion rod, a bracing rod pivotally connected to its bottom median portion, means 25

pivots connecting both aforesaid members with means rigidly mounted in the differential casing, and means pivotally connecting the forward end of the spring torsion rod to means suspended from the 30 automobile frame.

4. Spring torsion rod mechanism comprising a spring torsion rod having a plurality of opposite leaf members of graduated length disposed in like symmetrical 40 arrangement, a hinge member, means for bolting the hinge member to the central portion of the spring tension rod, a bracing rod pivotally secured to the hinge member, a vertical rod rigidly mounted in the differential casing and having its opposite ends pivotally connected to the rear ends of the spring torsion rod and of the bracing rod, a link member pivotally suspended 45 from a cross member of the automobile frame and having a pivotal connection with the front end of the spring torsion rod, whereby shocks are absorbed through deflection of the spring tension rod, and the differential and transmission relieved of 50 strain.
